UNITED STATES PATENT OFFICE.

FRANK L. ARMSTRONG, OF PHILADELPHIA, PENNSYLVANIA.

COMBINATION-TOOL.

SPECIFICATION forming part of Letters Patent No. 280,995, dated July 10, 1883.

Application filed February 27, 1883. (No model.)

To all whom it may concern:

Be it known that I, FRANK L. ARMSTRONG, a citizen of the United States, residing in the city and county of Philadelphia, State of Pennsylvania, have invented a new and useful Improvement in Combination-Tools, which improvement is fully set forth in the following specification and accompanying drawings, in which—

10 Figure 1 is a side elevation, partly sectional, of the combination-tool embodying my invention. Fig. 2 is a representation of different tools employed.

Similar letters of reference indicate corresponding parts in the two figures.

My invention consists of a tubular stem, which is formed with a socket for the reception of the shank of a tool, and a sliding rod, which carries on its outer end a mallet or hammer head, the latter adapted, owing to its weight, to impart blows to the tools, during the operation of which the tool may be rotated by proper manipulation of the stem. The stem and sliding rod may, however, be connected as one, so as to serve as a handle for the mallet or hammer head and tools—such as screw-drivers—all as will be herein-after set forth.

Referring to the drawings, A represents a hollow or tubular stem, one end of which is formed with a socket, B, for the reception of the shank of a tool, C, said socket having fitted to its wall a screw, D, which is adapted to tighten against said shank, and thus firmly secure the tool to the stem.

Within the stem A is a sliding rod, E, the inner end of which is formed with a head, a, which, when the rod is extended, abuts against the inner face of the end collar, b, of the stem

40 A, and thus prevents displacement of the rod.

To the outer end of the rod E is secured a mallet-head, F, which, by moving said rod in opposite directions, may be made to strike the stem A, and thus impart blows to the tool secured to the stem.

Formed with the mallet-head, on the side thereof, is a hammer-head, G, which, however, is not an essential feature, and to the inner end of said mallet-head is secured a pad, H, 50 of leather or other suitable flexible or elastic material, which is inserted in a recess in the

head F, and is adapted to strike the collar b or adjacent end of the stem A when blows of the mallet-head are imparted to the stem, and thus prevent fracture of the mallet-head and 55 stem.

To the collar b is fitted a screw, J, which may be tightened against the rod E, so that the latter may be rendered immovable in the stem A; or the rod and stem act as one. In 60 practice the parts enumerated are preferably formed of malleable iron, plated or otherwise finished.

Various tools may be fitted to the stem A, a few forms of which are shown in the drawings. When it is desired to use a tool such as a carpenter's, stone-cutter's, or other chisel, the screw J is loosened, and the stem A is held by one hand, while the mallet-head is grasped by the other hand and moved in and out of 70 the stem, so that blows are imparted to the head end of the stem, and consequently to the tool, the mallet-head acting as a weight for said purpose. A tool such as a drill requires that the stem is rotated during the intervals 75 of the blows. For a screw-driver, the rod E is moved into the stem and the screw J tightened, so that the stem and rod operate as one as a handle, the mallet-head readily serving as the bulbous end of the handle, as usual in 80 screw-drivers.

The mallet-head and hammer-head, if employed, are also serviceable for their purposes, the screw J being tightened and the stem forming the handle of the mallet or hammer as constituted; and other uses of the various parts may be made as will suggest themselves.

Having thus described my invention, what I claim as new, and desire to secure by Letters Patent, is—

1. A tubular stem, in combination with a sliding rod fitted thereto, said stem having at the lower end a tool-receiving socket, and at the upper or head end a collar, b, said rod carrying a hammer-head, the blows of which are 95 received by the collar, substantially as and for the purpose set forth.

2. A tubular stem having a tool-receiving socket at one end, in combination with a sliding rod connected with said stem, a weighted head 100 secured to said rod, and screws, one of which is fitted to the stem at the socket end and the

other at the head end, the blows imparted to the tool being received at said head end, substantially as and for the purpose set forth.

3. A tubular stem having a tool-receiving socket and tightening-screw for the tool, a sliding rod connected with said stem, a weighted head secured to said rod, and a pad attached to said head, the latter being recessed

on its inner end to receive said pad, the parts being combined and operating substantially as and for the purpose set forth.

FRANK L. ARMSTRONG.
